UNITED STATES PATENT OFFICE

CHARLES E. NEEDHAM, OF CHICAGO, ILLINOIS, ASSIGNOR TO THE RAYMOND BROTHERS
IMPACT PULVERIZER CO., OF CHICAGO, ILLINOIS, A CORPORATION OF ILLINOIS

JOURNAL FOR PULVERIZING MILL ROLLERS

Application filed January 5, 1929. Serial No. 330,501.

This invention relates to certain new and useful improvements in journals for pulverizing mill rollers, and more particularly to improved means for supporting and lubricating the bearings of a pulverizing roller, such as is used in a grinding or pulverizing mill of the general type shown, for example, in the patent to Raymond et al., No. 1,573,191, granted Feb. 16, 1926. In a mill of this type, a plurality of pulverizing rollers are pivotally suspended in a circular series from a rotating frame or spider, the rollers swinging out by centrifugal force against the inner surface of a fixed circular bull ring, where-by the material caught between the ring and rollers is pulverized.

The present invention relates to an improved form of journal support for one of these rollers, including an improved self-contained lubricating system for the bearings, and an improved means for supporting the renewable roller on a permanent supporting sleeve.

One object of this invention is to provide improved means for rotatably supporting a pulverizing roller upon a non-rotatable shaft, which is suspended in a substantially upright position.

Another object is to provide an improved self-contained circulating lubricating system for supplying lubricant to the bearing surfaces between the roller assembly and the non-rotatable shaft, the circulation of the lubricant being enforced by the centrifugal force developed by the bodily revolution of the rollers about the fixed central axis of the mill.

Another object is to provide improved means for supporting a removable and renewable annular roller upon a supporting sleeve which is permanently mounted upon the non-rotatable shaft. This means embodies the use of wedge-shaped pockets in the roller and adjusting and supporting bolts having wedge shaped heads engaged in the pockets, whereby tapered engaging surfaces on the roller and sleeve are drawn into engagement with one another.

Other objects and advantages of this invention will be more apparent from the follow-

ing detailed description of certain approved forms of apparatus embodying the principles of this invention.

In the accompanying drawings:

Fig. 1 is a central vertical section through one of the roller assemblies and adjacent parts of the mill structure.

Fig. 2 is a diagrammatic plan view, designed to illustrate the centrifugal forces developed by the revolution of the roller, where-by the oil circulation is enforced.

Fig. 3 is a sectional perspective showing a portion of the annular roller.

Fig. 4 is a sectional perspective through the upper bushing.

Fig. 5 is a detail elevation of one of the wedge-shaped bolts and the portion of the roller with which it engages.

At 1 is shown a portion of the rotating spider or frame which supports the rollers, this spider rotating about the fixed central axis of the mill, which is indicated at 2 in Fig. 2. The outer portion of the spider 1 comprises a plurality of yokes 3 arranged at spaced intervals about its circumference. In each yoke 3 is rotatably supported a trunnion shaft 4. The rocker 5 comprises a split collar 6 formed on one side thereof and adapted to be clamped about the trunnion shaft 4 by means of bolts 7. The tapered upper end 8 of the roller-supporting shaft 9 is adapted to be received in the central vertical tapered opening 10 in rocker 5. The upper end 11 of shaft 9 is threaded to receive the nut 12, which is screwed down into engagement with the top of rocker 5 to draw the tapered portion 8 of the shaft into tight engagement with the tapered opening 10 in the rocker. Nut 12 is locked in place by the bolt 13 threaded through the split portion 14 at one side of the nut. A key 15 secured in the shaft 9 engages a key-way 16 in the rocker 5 to prevent relative rotation between these members.

A central oil passage 17 extends axially through shaft 9 from top to bottom thereof, the lower end of this passage being open and the upper end normally closed by a threaded plug 17' which may be removed in order to add new oil through the upper end of 100

passage 17. The lower portion of passage 17 is preferably enlarged, as indicated at 18, to form a reservoir of greater capacity for the oil.

5 Below the upper tapered portion 8, the shaft 9 is externally cylindrical, but the upper cylindrical portion 19 is of somewhat smaller diameter than the lower cylindrical portion 20, there being an inwardly extending beveled surface 21 connecting these two cylindrical portions of the shaft. There is an outwardly extending annular collar 22 formed on the lower cylindrical portion of shaft 9.

15 The rotatable roller-supporting assembly comprises a lower sleeve 23 having an outwardly extending collar 24 at its upper end, and an upper sleeve 25 having an outwardly extending collar 26 at its lower end, the collars 24 and 26 being formed with a series of mating openings, through which bolts 27 provided with nuts 28 are secured, so as to clamp the two sleeves 23 and 25 in engagement with one another.

25 The lower sleeve 23 is open at its upper end, but closed at its lower end 29, so as to form a well 30 extending below the lower end of non-rotating shaft 9. A bushing 31 is interposed between sleeve 23 and shaft 9, this bushing having an outwardly extending collar or flange 32 at its upper end, secured to the sleeve 23 by pins 33. The upper surface of collar or flange 32 engages the under surface of collar 22 on the shaft, so as to limit the upward movement of sleeve 23 with relation to the shaft.

40 The upper sleeve or housing 25 has a smaller substantially cylindrical upper portion 34, between which and the shaft is interposed the bushing 35. The lower portion of sleeve 25 is flared outwardly to form a skirt 36 enclosing a chamber 37 which extends downwardly about the supporting collar 22. The flange 26 is formed on the lower end of skirt 36. The bushing 35 has a flange or collar 38 at its lower end extending outwardly into the chamber 37 and secured to the sleeve 34 by pins 39. A pair of thrust rings 40 and 41, which carry the load, are positioned in the chamber 37, the upper ring 40 being secured to the sleeve 25 of the rotating assembly by means of the pins 39, and the lower ring 41 being secured to the non-rotating collar 22 on the shaft 9, by means of pins 42.

45 The bushing 35 has a thicker upper portion 43 adapted to extend inwardly and engage the portion 19 of shaft 9 of smaller diameter, and this portion is formed with an inner spiral groove 44 which opens toward the shaft and terminates at its lower end against the beveled surface 21 on the shaft. This groove or thread 44 is of such direction and pitch that when the roller assembly is rotated about shaft 9 in the direction of the arrow *a*, in Fig. 2, any oil or other lubricant

that may find its way between the portion 43 of bushing 35 and the shaft will be caught and carried downwardly by this spiral groove. A packing or sealing means, consisting of a plurality of composition washers 45, held in place within the upper portion of sleeve 25 by a split metal ring 46, bears against the shaft to prevent dust entering between the top of the rotating assembly and the shaft. A skirt 47, formed on the lower end of rocker 5, extends down over the upper end of sleeve 25 into proximity to an outwardly extending collar 48 formed on the sleeve.

50 An oil duct or passage 49 is formed in the shaft 9 and extends inwardly and downwardly from its outer end, which opens from the inwardly beveled surface 21 of the shaft, to its lower end which connects with the central oil passage 17. This oil duct 49 is formed in that side of the shaft that faces the axis 2, around which the roller assembly bodily revolves, and preferably in that quadrant of the shaft facing in the direction of movement of the roller assembly about the mill, as will be described more in detail hereinafter.

55 The outer surface of the central portion of lower sleeve 23 is tapered downwardly from a larger upper portion to a smaller lower portion, as indicated at 50. An annular pulverizing roller 51 is provided with a correspondingly tapered inner surface 52 so that the roller may be drawn into snug engagement with the sleeve. The upper portion of roller 51 is formed with a plurality of pockets 53, opening into the tapered inner passage 52 and also through the upper face of the roller, the lower portions 54 of these pockets being wedge shaped with the large end of the wedge at the bottom, as indicated in Figs. 3 and 5. A plurality of bolts 55 have wedge shaped lower ends 56, which are adapted to be positioned in the wedge shaped ends 54 of the pockets, the upper threaded ends 57 of these bolts passing through mating openings in the sleeve flanges 24 and 26 and receiving nuts 58, whereby the supporting bolts 55 are drawn upwardly, so as to draw the roller 51 into snug engagement with the tapered surface on sleeve 23. The wedge shaped lower ends 56 of the bolts will engage the upwardly tapering side surfaces of the pockets 54 so that the bolts will be assured of at least a two-point contact with the roller. This avoids the necessity for careful machining of the interior of the pockets 53 or of the bolt heads 56. By simply removing the nuts 58, the roller 51 may be driven off from the sleeve 23 without dismantling the remainder of the roller assembly, and replaced by a new roller 51 in case the first roller has become worn. The bolts 55 may be inserted in the pockets in the new roller and re-used as in the first installation.

60 The roller 51 is adapted to engage the bull 130

ring 59, which is fixed to the stationary outer frame 60 of the mill. Material caught between the ring 51 and bull ring 59 will be pulverized in the well known manner. It will be apparent that as the roller assembly is revolved bodily about the central axis 2 of the mill in the direction of the arrow *b* in Fig. 2, centrifugal force will tend to throw the roller 51 outwardly in the direction of the arrow *c*, thus forcing the roller into engagement with the bull ring and causing it to rotate thereon in the direction of the arrow *a*.

Assuming that the reservoir 18 and the well 30 have been filled with lubricant inserted through the passage 17, the rapid rotation of the roller assembly, including the sleeve 23 about the central axis of shaft 9, will tend to throw the oil in well 30 outwardly and cause it to flow up between the relatively rotating bearing surfaces on the shaft and bushing 31, this oil being replaced by oil from reservoir 18, which is forced downwardly by gravity. This film of oil will flow up until it reaches the chamber 37, wherein centrifugal force will throw the oil out so as to fill this chamber about the relatively rotating thrust rings 40 and 41. This oil, being replaced by new oil flowing up from the well 30, will pass in between the bearing surfaces of thrust rings 40 and 41 and thence upwardly between the bushing 35 and the shaft 9. This upwardly flowing oil will force the oil ahead of it inwardly along the beveled surface 21. Any oil that continues to flow upwardly will be caught in the spiral channel 44 and carried downwardly against the beveled surface 21. There is also a centrifugal force acting on this oil that has reached the bevel surface 21, this force being due to the bodily revolution of the roller assembly about the central axis 2 of the mill. There is a force tending to throw this oil in the direction of the arrow *c*, Fig. 2. There is also a force of inertia opposing the movement of the roller and the oil and acting in the direction of the arrow *d*. The combination of these several forces will act in some such direction as *e* and tend to concentrate the oil at the side of the shaft opposite this arrow *e*. The oil duct 49 is positioned substantially in line with the direction of action of this centrifugal force, so that this force will tend to make the oil flow inwardly through this duct to the central passage 17 in the shaft. The exact direction in which this force acts may vary, and if the duct 49 is located any where in that half of the shaft which faces toward the central axis 2, but preferably in the quadrant that faces the direction of revolution *b* of the shaft, the oiling system will operate satisfactorily. The oil which flows over the upper beveled surface 21 will be carried by centrifugal force against the outer surface of the rotating bushing 35, but will be held against further upward

travel, due to the bushing rotating about the central axis of the shaft 9, this force opposing the inward movement of the oil along tapered surface 21. As this accumulated oil is carried around opposite the mouth of duct 49, part of this oil will be caught and forced inwardly by centrifugal force through the duct 49 and into the central passage 17, wherein it will flow down by gravity to join the oil supply in reservoir 18. Any oil that may find its way up along bushing 35 about the tapered surface 21 will be caught in channel 45 and carried downwardly to this beveled surface and thence forced to flow inwardly through duct 49. It is desirable that a very small quantity of oil find its way past the bushing 43, so as to lubricate the engaging surfaces of the packing 49 and shaft 19. The amount of oil used in this manner will be comparatively small. It will be noticed that there is a continuous circulation of the oil downwardly through the shaft 9 and upwardly between the shaft and the bushing and thence inwardly through duct 49 to the oil supply within the shaft. This continuous circulation of the oil is enforced by the combined action of gravity and the centrifugal forces developed by rotation of the roller about the central axis of the shaft and the bodily revolution of the roller about the central axis 2 of the mill. The oil supply may be replenished when necessary by removing the plug 17' at the upper end of the passage 17.

The overlapping surfaces of the shaft and bushing 35 at the beveled surface 21 will permit a certain amount of wear to take place at one side of the bushing and still provide a pocket in which oil will be trapped and carried around to the duct 49, despite the fact that a clearance will be developed at that side of the shaft opposite the point where the wear takes place.

I claim:

1. In an apparatus of the character described, a shaft, means for suspending the shaft in a substantially vertical position, the shaft being held in the suspending means against rotation about its own axis but being bodily revoluble about a fixed vertical axis, there being a central lubricant passage extending axially through the shaft, a roller assembly rotatably supported on the shaft and enclosing the lower end of the shaft so as to form a lubricant well below the shaft, the lubricant passage in the shaft communicating with this well, the upper portion of the shaft being of a smaller diameter so as to form an inwardly extending and upwardly facing annular shoulder on the outer surface of the shaft, a bushing interposed between the roller assembly and shaft and rotating with the roller, this bushing having an upper portion of smaller inner diameter so as to engage the shaft above the shoulder, means for sealing

the joint between the upper end of this bushing and the shaft, and an oil duct leading from the surface of the shoulder on the shaft to the central oil passage, the duct being so positioned that centrifugal force will cause oil to flow inwardly through this duct.

2. In an apparatus of the character described, a shaft, means for suspending the shaft in a substantially vertical position, the shaft being held in the suspending means against rotation about its own axis but being bodily revoluble about a fixed vertical axis, there being a central lubricant passage extending axially through the shaft, a roller assembly rotatably supported on the shaft and enclosing the lower end of the shaft so as to form a lubricant well below the shaft, the lubricant passage in the shaft communicating with this well, the upper portion of the shaft being of a smaller diameter so as to form an inwardly extending and upwardly facing annular shoulder on the outer surface of the shaft, a bushing interposed between the roller assembly and shaft and rotating with the roller, this bushing having an upper portion of smaller inner diameter so as to engage the shaft about the shoulder, means for sealing the joint between the upper end of this bushing and the shaft, and an oil duct leading from the surface of the shoulder on the shaft to the central oil passage, this duct being positioned in the side of the shaft which faces the fixed axis about which the shaft revolves.

3. In an apparatus of the character described, a shaft, means for suspending the shaft in a substantially vertical position, the shaft being held in the suspending means against rotation about its own axis but being bodily revoluble about a fixed vertical axis, there being a central lubricant passage extending axially through the shaft, a roller assembly rotatably supported on the shaft and enclosing the lower end of the shaft so as to form a lubricant well below the shaft, the lubricant passage in the shaft communicating with this well, the upper portion of the shaft being of a smaller diameter so as to form an inwardly extending and upwardly facing annular shoulder on the outer surface of the shaft, a bushing interposed between the roller assembly and shaft and rotating with the roller, this bushing having an upper portion of smaller inner diameter so as to engage the shaft above the shoulder, means for sealing the joint between the upper end of this bushing and the shaft, there being a spiral groove formed in the inner surface of the upper portion of the bushing with its lower end terminating at the shoulder and its open side engaging the shaft, and an oil duct leading from the surface of the shoulder on the shaft to the central oil passage, the duct being so positioned that centrifugal force will cause oil to flow inwardly through this duct.

4. In an apparatus of the character de-

scribed, a shaft, means for suspending the shaft in a substantially vertical position, the shaft being held in the suspending means against rotation about its own axis but being bodily revoluble about a fixed vertical axis, there being a central lubricant passage extending axially through the shaft, a roller assembly rotatably supported on the shaft and enclosing the lower end of the shaft so as to form a lubricant well below the shaft, the lubricant passage in the shaft communicating with this well, the upper portion of the shaft being of a smaller diameter so as to form an inwardly extending and upwardly facing annular shoulder on the outer surface of the shaft, a bushing interposed between the roller assembly and shaft and rotating with the roller, this bushing having an upper portion of smaller inner diameter so as to engage the shaft above the shoulder, means for sealing the joint between the upper end of this bushing and the shaft, there being a spiral groove formed in the inner surface of the upper portion of the bushing with its lower end terminating at the shoulder and its open side engaging the shaft, and an oil duct leading from the surface of the shoulder on the shaft to the central oil passage, this duct being positioned in the side of the shaft which faces the fixed axis about which the shaft revolves.

5. In an apparatus of the character described, means for suspending the shaft in a substantially vertical position, the shaft being held in the suspending means against rotation about its own axis but being bodily revoluble about a fixed vertical axis, the shaft being formed with an upper portion of reduced diameter so as to provide an upwardly facing annular shoulder connecting the outer cylindrical surfaces, the shaft also being formed at a location beneath this shoulder with an outwardly extending annular flange, there being a central oil passage extending axially through the shaft, a roller assembly comprising a plurality of connected members supported for rotation about the shaft and suspended thereon by the annular flange, there being an oil well in one of these members below the shaft with which the central passage communicates, there being a plurality of bushings secured in the assembly and engaging the shaft, the upper bushing having a portion of smaller inner diameter engaging the shaft above the shoulder, means for sealing the joint between the upper portion of this bushing and the shaft, the bushing being formed with a spiral channel in its inner surface with its open side engaging the shaft and its lower end terminating at the shoulder, and an oil duct in the shaft leading from the surface of the shoulder to the central passage, this duct being located in that side of the shaft which faces the fixed axis about which the shaft revolves.

6. In an apparatus of the character described, means for suspending the shaft in a substantially vertical position, the shaft being held in the suspending means against rotation about its own axis but being bodily revoluble about a fixed vertical axis, the shaft being formed with an upper portion of reduced diameter so as to provide an upwardly facing annular shoulder connecting the outer 5 cylindrical surfaces, the shaft also being formed at a location beneath this shoulder with an outwardly extending annular flange, there being a central oil passage extending axially through the shaft, a roller assembly 10 comprising a plurality of connected members supported for rotation about the shaft and suspended thereon by the annular flange, there being an oil well in one of these members below the shaft with which the central 15 passage communicates, there being a plurality of bushings secured in the assembly and engaging the shaft, the upper bushing having a portion of smaller inner diameter engaging the shaft above the shoulder, means 20 for sealing the joint between the upper portion of this bushing and the shaft, and an oil duct in the shaft extending from the surface of the shoulder to the central passage, this duct being located in that side of the shaft 25 30 which faces the fixed axis about which the shaft revolves.
